H. E. CONRAD,
SECTION INSULATOR AND SWITCH,
APPLICATION FILED JULY 15, 1920.

Patented Dec. 5, 1922.

INVENTOR
Harry E. Conrad
BY
John D. Morgan
ATTORNEY

UNITED STATES PATENT OFFICE.

HARRY E. CONRAD, OF NEWARK, NEW JERSEY.

SECTION INSULATOR AND SWITCH.

Application filed July 15, 1920. Serial No. 396,516.

To all whom it may concern:

Be it known that I, HARRY E. CONRAD, a citizen of the United States, residing at Newark, in the county of Essex and State 5 of New Jersey, have invented certain new and useful Improvements in Section Insulators and Switches, of which the following is a specification.

The invention relates to switches and insulating mechanism for trolley wires and the like, and in certain of its features the invention relates to such devices adapted to control the current supply for sections and branches of a trolley circuit system and in 15 certain aspects thereof, it relates more particularly to such devices adapted for use in coal mines and elsewhere where special conditions are to be met.

Objects and advantages of the invention 20 will be set forth in part hereinafter and in part will be obvious herefrom or may be learned by practice with the invention; the same being realized and attained by means of the instrumentalities and combinations 25 pointed out in the appended claims.

The invention consists in the novel parts, constructions, arrangements, combinations and improvements herein shown and described.

30 The accompanying drawings, referred to herein and constituting a part hereof, illustrate one embodiment of the invention, and together with the description serve to explain the principles of the invention.

35 Of the drawings:

Fig. 1 is a top plan of a switch mechanism embodying the invention;

Fig. 2 is a side elevation, looking at the adjacent side of Fig. 1;

40 Fig. 3 is a transverse vertical section taken on the line 3—3 of Fig. 1;

Fig. 4 is a transverse vertical section taken on the line 4—4 of Fig. 2;

45 Fig. 5 is a perspective view of one of the trolley line terminals; and

Fig. 6 shows the device in a working position, as in a mine, and with a ground connection to the track.

The invention relates to a switch and insulating device whereby various sections or branches of a trolley wire system may be connected to and cut off from the source of current supply and connected to or cut off from other sections or branches of the trolley

wire system. The invention provides 55 such a device which is adapted to be placed directly in the trolley wire or circuit, the trolley running directly along and past the device. In certain of its aspects, the invention is especially designed to meet working conditions in mines and elsewhere, and also to meet the requirements of legislation directed to matters of safety, workmen's compensation, and like subjects.

The invention in certain of its features is 65 also directed to provide an interchangeable device, that is, one in which the parts may be substituted end for end, that is, where they may be "left handed" or "right handed" at will as desired, without disturbing 70 the mounting of the device, or when it is desired to change the location of the device. In certain states, and in certain classes of work, such as mine work, it is prescribed by law or is customary 75 to carry the trolley at or near one side of the trackway, and to require or to have the switch operating on the side of the device toward the track, both as a matter of safety from the current and for convenience in 80 places of relatively small height or otherwise contracted space. Other features and advantages of the invention will be pointed out in connection with the detailed description of the present preferred embodiment. 85

Referring now in detail to the embodiment of the invention illustrated by way of example in the accompanying drawings, a supporting and insulating member 1 for the spaced apart trolley wire terminals and the connecting and disconnecting switch is provided, which is of wood, fiber or other insulating material, and is adapted to be supported from a mine roof or wall, or other convenient support adjacent to its location. 90 Such insulating support 1 serves as the supporting and positioning means for the adjacent ends or terminals of two sections of the trolley wire, with an air gap between the terminals, and for a switch carried movable 95 to open and to close the circuit past said gap in the trolley wire or circuit.

The insulating support 1 is fastened to its supporting means in any suitable or convenient manner, and as embodied a bifurcated lug or bracket 2 fits on the top or back of support 1 and has plates or arms 3 and 4, extending downwardly upon either side

of said support, and a bolt 5 passes through the plates or arms and through the insulator body 1 to fasten them together. An upwardly projecting boss 6 of the supporting bracket is internally screw-threaded, as at 7, to take the screw-threaded shank of an expansion bolt 8 or other suitable fastening device, which is secured to the mine roof or other suitable support.

10 Referring now to the terminals of the trolley wires or circuit mounted upon the insulating support 1, the two terminals, separated by the air gap may be the same or similar in form and construction, and a single description will suffice therefor. Each of the terminals 10 has a flat surface 11 adapted to fit against a face, preferably the bottom face, of the support 1, which support is preferably of rectangular shape. The terminal is provided with an end shoulder 12, which projects past the end of the support 1 (Figs. 1, 2 and 5), to position the terminal longitudinally with respect to the support 1 and to prevent longitudinal displacement thereof with respect to the support.

15 The terminal 10 is likewise provided with means for preventing transversal or side-wise displacement thereof with respect to the insulating support 1, and as embodied, 30 a series of lugs 13, shown as two in number on either side of the terminal 10 receive the support 1 between them and project past the corresponding edges and along the corresponding sides of the support 1, to prevent swiveling or lateral displacement of the terminal as stated. Means are provided for attaching the terminal 10 to the support 1, and as embodied, screw bolts 15 (Figs. 1, 2 and 3) pass through the insulating support 1, and are in screw-threaded engagement with internally screw-threaded holes 16 formed in the terminal 10.

20 The two terminals 10 are mounted upon the same face or side of support 1, and are held in permanent position relatively to each other upon the support without danger of displacement, and with an insulating air gap between their adjacent ends. The adjacent ends of the terminals 10 are transversely and parallelly beveled relatively to the length of the device, the forward end of one terminal 10 extending past the rear end of the other, considered transversely of the support 1, as shown at 17, thereby providing a continuous and smooth track for a passing trolley. The terminals 10 are shaped to fit more or less closely the trolley wheel or shoe, to provide a track and guide for the trolley, and to facilitate 25 its easy passage from the trolley wire to a terminal, from one terminal to another across the air gap, and thence to the other trolley wire.

30 As embodied, the terminals 10, respectively, are adapted to receive the trolley

wires 18 of the two sections of the circuit at their exterior ends 19, the trolley wire passing into the longitudinally apertured interior of the corresponding terminal, and being clamped in contact therewith by one 70 or more clamping screws 20, screw-threaded into the wall of the terminal 10 and bearing upon the wire 18 within the interior of the terminal. The terminals present a curved surface on their exterior or under side to 75 the trolley, and preferably increase in cross-section from their outer ends toward their inner ends.

Referring now to the details of construction of the switch which makes and breaks 80 the trolley circuit past the insulating terminals 10, in accordance with certain features of the invention, and as already indicated, the switch is reversible end for end. As embodied, the switch is positioned on the 85 side of support 1 and is provided with a blade 24, having a handle 23, preferably inclined outwardly as shown in Figs. 1 and 2 as a matter of safety and convenience. One end of blade 24 passes between, and is pivotally mounted upon two terminal plates 25 and 26, spaced apart to receive the switch blade therebetween in the usual manner, which plates are supported by and electrically connected to one of the trolley terminals 10. As embodied, the plates at their 90 inner ends are formed to contact together, face to face, and lie within a corresponding shaped recess 29 in the inner face of terminal 10 to make electrical contact therewith. 95 At their said inner contacting ends the plates are apertured to receive a screw bolt 27, which is screw-threaded into a hole 30 in the body of the terminal 10, the head of the bolt resting within a cut-out or recessed 100 portion in the face of the supporting insulator 1.

105 This construction is shown in Fig. 4 for the corresponding pair of plates at the other end of the device. The two pairs of plates 110 are alternatively used as the pivotal support for the switch blade 24 or for the terminals which cooperate therewith to make or break the circuit.

110 For the pivotal switch mounting, plates 25 and 26, and also the blade 24 of the switch are apertured to receive a bolt 31, having locking nuts 32, and having also, preferably, spring washers 33 and 34, whereby the switch blade 24 is pivotally supported between the plates 25 and 26, and good electrical contact is maintained therebetween.

115 In a corresponding position with respect to the other trolley terminal 10 there are two other plates 36 and 37, which in the illustrated arrangement constitute the switch terminals for the corresponding trolley terminal 10, the switch blade passing between the plates 36 and 37 to close the circuit in the usual manner for knife switches. 125 130

This pair of plates 36 and 37, the pair 25 and 26, are interchangeably or alternatively used as either the pivot bearing or the co-operating terminals for the switch, as 5 already referred to. The mounting and connections of the plates 36 and 37 are the same as for the plates 25 and 26, already described, and as shown in Figs. 1 and 4. In plate 36, Fig. 1, is shown an aperture 39, there being 10 a corresponding aperture in the plate 37, and these are adapted to receive the bolt 31, in the same manner as is shown for plates 25 and 26 in Fig. 2, when the switch blade 24 is to be mounted reversely. In that case, the 15 plates 25 and 26 would serve as the terminals with which the blade 24 would pass into and out of contact to close and open the circuit, as it does in the present arrangement with plates 36 and 37.

20 Means are provided for grounding the switch in the open position, and as embodied a contact plate 40 (Figs. 1, 2 and 3) has a part 41 adapted to form close sliding contact with the switch blade 24 in open position, 25 and has an angled part 42 contacting with and supported upon the side of the insulating support 1, the part 42 being apertured to receive a bolt 43 passing therethrough and into the insulating support 1. On the opposite side of the support 1 is a plate 44, having a part 45 resting against and supported upon the side of the insulating support 1, said part 30 45 being apertured to receive the bolt 43. The bolt 43 thus serves to support both the 35 member 40 and 44 upon the insulating support 1, and also to form an electrical connection therebetween. The member 44 is shaped and apertured at 46 to receive a ground wire 47, which may be grounded to 40 the track rail 48, as shown in Fig. 6. The ground wire 47 is preferably provided with a detachable connection, such as a ferrule 49, making a tight but removable fit, within the part 46 of member 44. The ground connection is also reversible end for end of the 45 device with the switch 24, and for this purpose, a bolt 50 is provided at the opposite end of the insulating body 1, whereby the members 40 and 44 may be shifted to the opposite end of the device whenever the switch 50 24 is changed or mounted in reverse position.

Means are provided for locking the switch either in open or closed position, to guard it 55 against accidental or malicious displacement, and as embodied each of the trolley terminals 10 is provided with a lug 51, having an aperture 52 through which may be passed a locking device which also encircles 60 or otherwise effectually engages the switch blade or lever 24.

The invention in its broader aspects is not limited to the specific mechanisms shown and described but departures may be made therefrom within the scope of the accompanying

claims without departing from the principles of the invention and without sacrificing its chief advantages.

What I claim as my invention is:—

1. A trolley circuit insulating and switch- 70 ing device including in combination an insulating support extending lengthwise of the trolley line, two trolley line terminals spaced apart by an air gap and mounted on said support and having their adjacent ends bevelled transversely to said support and substantially parallel to each other, the forward end of one terminal extending past the rear end of the other terminal, two switch terminals one connected to one trolley line terminal and another to the other trolley line terminal, and a switch blade adapted to be interchangeably pivotally mounted on either of the switch terminals and to cooperate with the other switch terminal to open and 80 close the circuit. 85

2. A trolley circuit insulating and switch- 90 ing device including in combination an insulating support extending lengthwise of the trolley line, supporting means therefor upon the top side thereof, two trolley line terminals spaced apart by an air gap and mounted on said support and having their adjacent ends bevelled transversely to said support and substantially parallel to each other, the forward end of one terminal extending past the rear end of the other terminal, two switch terminals one connected to one trolley line terminal and another to the other trolley line terminal, and a switch blade adapted to be 95 interchangeably pivotally mounted on either of the switch terminals and to cooperate with the other switch terminal to open and close the circuit. 100

3. A trolley circuit insulating and switch- 105 ing device including in combination an insulating support extending lengthwise of the trolley line, two trolley line terminals mounted upon a face of said support and separated by an air gap the adjacent ends of the terminals being bevelled transversely to the support and substantially parallel to each other, the forward end of one terminal extending past the rear end of the other terminal, 110 means for preventing longitudinal displacement of the terminals with respect to the support to insure the maintenance of the air gap and a switch movable to bridge the air gap. 115

4. A trolley circuit insulating and switch- 120 ing device including in combination an insulating support extending lengthwise of the trolley line, two trolley line terminals mounted upon a face of said support and separated by an air gap the adjacent ends 125 of the terminals being bevelled transversely to the support and substantially parallel to each other, the forward end of one terminal extending past the rear end of the other terminal, means for preventing transverse dis- 130

placement of the terminals with respect to the support to insure the maintenance of the air gap and a switch movable to bridge the air gap.

- 5 5. A trolley circuit insulating and switching device including in combination an insulating support, two trolley line terminals spaced apart by an air gap and mounted on said support, two switch terminals one connected to one trolley line terminal and another to the other trolley line terminal, and a switch blade adapted to be interchangeably pivotally mounted on either of the switch terminals and to cooperate with the other switch terminal to open and close the circuit, and a ground connection for the switch when in the open position.
- 10
- 15

6. A trolley circuit insulating and switching device including in combination an insulating support, two trolley line terminals 20 spaced apart by an air gap and mounted on said support, two switch terminals one connected to one trolley line terminal and another to the other trolley line terminal, a switch blade adapted to be interchangeably 25 pivotally mounted on either of the switch terminals and to cooperate with the other switch terminal to open and close the circuit, and a disconnectable ground connection for the switch when in the open position. 30

In testimony whereof, I have signed my name to this specification.

HARRY E. CONRAD.
